Application January 3, 1945, Serial No. 571,167

5 Claims. (Cl. 62—119)

1

The present invention relates to refrigeration and more particularly to a refrigeration system including a novel evaporator construction to adapt the system for air conditioning.

While the present invention may be used with other absorption refrigeration systems, it is particularly adapted for use in a system of the type illustrated and described in the application for United States Letters Patent of Albert R. Thomas, Serial No. 560,214, filed October 25, 1944, entitled "Refrigeration." The refrigeration system illustrated and described in the Thomas application operates in a partial vacuum and utilizes water as a refrigerant and a saline solution as an absorbent. The refrigerant and absorbent are introduced into the system as a water solution of a salt such as lithium chloride, lithium bromide, or the like and the absorbent occurs in the system as a dilute or concentrated water solution of the salt.

One of the objects of the present invention is to provide an evaporator or cooling element having vertical tubes extending between upper and lower headers and so constructed and arranged as to distribute liquid refrigerant equally to the plurality of tubes.

Another object is to provide an evaporator of the type indicated in which the liquid refrigerant is supplied to the open upper end of each tube in a thin sheet or film around its entire periphery for gravity flow therethrough.

Another object is to provide an evaporator having vertical tubes of the type indicated with serrations on the inner periphery of each tube to impede the flow of liquid refrigerant and maintain a thin film of the liquid refrigerant throughout its length.

Another object is to provide an evaporator of the type indicated having a pump circuit for recirculating the refrigerant from the lower header to the upper header.

Still another object is to provide an evaporator of the type indicated which is adapted to accommodate the large volumes of refrigerant vapor formed in a vacuum system.

These and other objects will become more apparent from the following description and drawing in which like reference characters denote like parts throughout the several views. It is to be expressly understood, however, that the drawing is for the purpose of illustration only and not a definition of the limits of the invention, reference being had for this purpose to the appended claims.

In the drawing:

2

Fig. 1 is a diagrammatic view of an absorption refrigeration system incorporating the evaporator of the present invention; and

Fig. 2 is a longitudinal sectional view of the upper portion of an evaporator tube showing the internal helical groove forming a plurality of serrations on the inner periphery of the tube and a wick to facilitate the initial wetting of the inner surface of the tube.

10 In the drawing, the invention is shown applied to a refrigeration system of the type illustrated in the Thomas application referred to above. In a refrigeration system of this type a liquid refrigerant such as, for example, water is introduced into the evaporator 10, later to be described in detail, from a condenser 11 through a path of flow including a U-shaped tube 12. The U-shaped tube 12 has one end connected to a sump 13 at the bottom of the condenser 11 and its opposite end extends through the top of the evaporator 10. The refrigerant vapor formed in the evaporator 10 flows to an absorber 14 where the vapor is absorbed in a liquid absorbent such as, for example, a concentrated water solution of lithium chloride or lithium bromide. The absorber 14 is in the form of a horizontally arranged cylindrical drum positioned below the evaporator 10. A pipe 15 extends upwardly from the top of the absorber 14 and is connected to the evaporator 10 to provide a path of flow for refrigerant vapor from the evaporator to the absorber.

15 Absorption liquid enriched with refrigerant or, in other words, a dilute salt solution is conducted from the absorber 14 to the base of a generator 16 in a path of flow including a conduit 17, pump 18, conduits 19 and 20, liquid heat-exchanger 21 and conduit 22. The generator 16 comprises a plurality of riser tubes 23 enclosed within an outer shell 24 to provide a chamber therebetween. 20 Steam is supplied to the chamber in the generator 16 from a boiler 25 through a conduit 26. For purposes of illustration a manually operable valve V is shown in the conduit 25 for controlling the amount of steam supplied to the generator 16 but it will be understood that a suitable automatically operable valve may be substituted for controlling the amount of steam delivered to the generator 16 in accordance with the load. The boiler 25 is provided with fire tubes 27 to which heat is supplied from suitable fuel burners 28. 25 An outlet vent 29 is provided adjacent the upper end of the steam chamber in the generator 16 and a condensate return line 30 is provided adjacent the base thereof. The heating of the riser tubes 23 by the steam causes refrigerant vapor to

be expelled from the absorption solution and such expelled vapor is effective to raise the absorption solution in the tubes by gas or vapor lift action. The expelled vapor passes from the upper ends of the riser tubes 23 into a vapor separator 31 and thence flows through a conduit 32 to the condenser 11 where the vapor is liquefied. Liquid refrigerant formed in the condenser 11 flows through the U-shaped tube 12 to the evaporator 10, as explained above, to complete the refrigeration cycle.

The raised absorption solution from which refrigerant vapor has been expelled is conducted from the upper portion of the generator 16 to the absorber 14 in a path of flow including a conduit 33, liquid heat exchanger 21 and conduit 34. The end of the conduit 34 extends into the upper portion of the absorber 14 adjacent the inlet from the pipe 15 and has a plurality of apertures or nozzles therein to provide a distributing pipe 35 for dividing the absorption solution as it is introduced into the absorber to promote absorption of the refrigerant vapor. The heat liberated by the absorption of refrigerant vapor in absorber 14 is taken up by a cooling medium such as, for example, water which flows upwardly through vertically disposed banks of pipes or coils 36 in the absorber. The cooling water is introduced into the lower ends of the banks of pipes 36 from a supply main 37 and is discharged from the upper ends of the banks of pipes through a conduit 38. Conduit 38 is connected to the condenser 11 so that the cooling water also may be utilized to effect cooling of the condenser. The cooling water is discharged from the condenser 11 through a conduit 39.

The system operates in a partial vacuum with the generator 16 and condenser 11 operating at one pressure and the evaporator 10 and absorber 14 operating at a lower pressure. The pressure differential between the high and low pressure sides of the system is maintained by a liquid column in the up-leg of the U-shaped tube 12 between a condenser 11 and evaporator 10. A similar liquid column also is present in the conduit 34 connecting the absorber 14 and liquid heat exchanger 21. The pump 18 connected between the absorber 14 and liquid heat exchanger 21 also maintains the pressure differential between the absorber and generator 16.

The absorption solution in the absorber 14 is circulated continuously through an auxiliary loop circuit to promote absorption of the refrigerant vapor. The auxiliary loop circuit for the absorption solution comprises the conduit 17, pump 18 and conduit 19. The upper end of the conduit 17 extends into a sump 40 in the bottom of the absorber 14 and the lower end of the conduit is connected to the inlet of the pump 18. Conduit 19 is connected at one end to the outlet from the pump 18 and its opposite end extends throughout the length of the absorber 14 adjacent the top thereof. A series of nozzles 41 are provided in the end portion of the conduit 19 extending into the absorber 14 to provide a liquid distributing pipe 42 for dividing the absorption liquid into a fine spray as it is delivered to the absorber. During operation of the refrigeration system, part of the circulating absorption solution is diverted from the conduit 19 through the conduit 20 and liquid heat exchanger 21 to the generator 16 as previously described.

An overflow conduit 43 is provided between the separating chamber 31 and the absorber 14 and

the upper end of the conduit in the separating chamber is protected by a shield 44.

When relatively large refrigeration units utilizing water as a refrigerant are used for air conditioning, a uniform distribution and evaporation of refrigerant in different parts of the evaporator cannot be obtained in the usual types of evaporators due to the low pressure and great volume of refrigerant vapor. A flooded type evaporator cannot be used advantageously in such a refrigeration system because of the hydrostatic head of refrigerant in such an evaporator which raises the boiling point progressively from the top to the bottom of the evaporator and renders the greater portion of its surface ineffective for the transfer of heat. To avoid such hydrostatic head, it is desirable to maintain a thin film of the liquid refrigerant on the internal surfaces of the evaporator. With relatively small units using water as a refrigerant, it is the practice to flow the refrigerant from the top to the bottom of the evaporator in a shallow stream through a series of substantially horizontal tubes. In such small units a substantial wetting of the interior surfaces of the tubes is obtained and the design can be such that all of the refrigerant will be evaporated during a single pass through the evaporator at full load conditions. With large units, however, due to the increased amount of liquid refrigerant supplied to the evaporator it is practically impossible to maintain a thin film of refrigerant on the interior surfaces of such a series arrangement of horizontal tubes and the liquid refrigerant in the first tubes of the evaporator is apt to be blown out of the tubes by the rapidly expanding refrigerant vapor. Furthermore, it is difficult to design a horizontal tube evaporator for a large unit which will vaporize all of the refrigerant during a single pass therethrough under varying load conditions.

In accordance with the present invention a novel form of air conditioning evaporator is provided for use with relatively large refrigeration units. The evaporator 10 comprises a casing 50 forming a central rectangular opening 51 through which the air to be conditioned may be circulated. The casing is of generally hollow construction to provide an upper header 52 above the opening 51, a lower header 53 below the opening and a relatively large passageway 54 at one side of the opening. The bottom wall of the upper header 52 constitutes a horizontal tube sheet 55 and the top wall of the lower header 53 constitutes a tube sheet 56. The end of the lower header 53 opposite the passageway 54 extends horizontally and vertically to provide a pump chamber 57. One end of the upper header 52 converges into a cylindrical pipe section 58 having a flange 59 at its end for connection to the pipe 15.

A plurality of vertical pipes or cooling tubes 60 extend across the opening 51 and through the tube sheets 55 and 56 in the upper and lower headers 52 and 53. The upper end portions of the tubes 60 extend above the tube sheet 55 in the upper header 52 with all of the ends arranged at the same level in a horizontal plane. A wall 61 extends upwardly from the tube sheet 55 and between the side walls of the header 52 to provide a dam for maintaining a pool of liquid refrigerant around the upwardly projecting ends of the tubes 60. While a single row of the tubes 60 are illustrated in the drawing, it will be understood that a plurality of rows of tubes may be provided and the tubes are provided with fins 63 for in-

creasing the heat transfer. The internal surface of the tubes 60 are roughened or serrated to impede the flow of refrigerant therethrough and maintain a thin film of liquid refrigerant thereon. As illustrated in Fig. 2, the serrations on the interior of each tube is formed by an internal helical groove 64 in which refrigerant flows from the top to the bottom of the tube by gravity. Due to the size and shape of the helical groove 64 the liquid refrigerant creeps up along the surface of the tube between adjacent grooves due to capillary action to wet the entire surface of the tube and form a film of liquid refrigerant thereon. While not essential to the operation of the evaporator 10, a starting device 62 may be provided on the upwardly projecting end of each tube 60 to initially wet the inner surface of the tube before the liquid rises to the level of the upper end of the tube. As illustrated in Fig. 2, the starting device is formed by a fine mesh metallic screen looped over the sides of the upwardly projecting end of the tube. In place of a metal screen a fabric sleeve or wicking may be used.

The liquid refrigerant in the lower header 53 is recirculated through the evaporator 10 by a pump 65 in the pump chamber 57. The pump 65 is positioned below the liquid level in the lower header 53 and the pump is driven by a shaft 66 extending from an hermetically sealed motor 67 mounted on the evaporator casing. A conduit 68 is connected to the outlet from the pump 65 and extends upwardly and then horizontally throughout substantially the entire length of the upper header 52. The portion of the conduit 68 extending into the header 52 has a series of outlet apertures or nozzles 69 and constitutes a liquid distributing pipe 70 for supplying the recirculated refrigerant to the upper header.

An overflow conduit 75 is provided in the evaporator 10 to prevent the accumulation of an excessive amount of liquid refrigerant therein. The upper end of the conduit 75 extends into the evaporator 10 to a predetermined height above the bottom thereof and below the lower ends of the tubes 60. The opposite end of the conduit 75 may be connected to any part of the refrigeration system and as herein illustrated it is connected to the conduit 22 adjacent the base of the generator 16. When the level of the liquid refrigerant in the evaporator 10 rises to a level above the upper end of the conduit 75 the liquid refrigerant will overflow to the base of the generator 16 to dilute the absorption solution and maintain the concentration below the saturation point at which crystallization and precipitation of salt from the solution will occur. One form of the invention having now been described in detail the mode of operation is explained as follows.

Steam supplied to the generator 16 vaporizes the refrigerant therein which flows upwardly through the tubes 23 and raises the absorption solution by vapor lift action. The refrigerant vapor flows from the separating chamber 31 through a conduit 32 to the condenser 11 where the vapor is condensed to a liquid. The liquid refrigerant flows from the condenser 11 through the U-shaped tube 12 into the upper header 52 of the evaporator. Due to the dam 51 in the upper header 52, a pool of the liquid refrigerant accumulates around the end portions of the evaporator tubes 60 projecting above the tube sheet 55. When a sufficient amount of liquid refrigerant has accumulated in the header 52, the liquid level will rise to the horizontal level of the upper ends of the tubes 60 and will flow into the tubes at the

inner periphery thereof. Due to the equal height of the ends of the evaporator tubes 60 above the tube sheet 55 the liquid refrigerant will be distributed equally in all of the tubes 60 and will be supplied to each tube in a thin film around its entire inner periphery. When a starting device 62, as illustrated in Fig. 2, is provided on the upwardly projecting end of each of the tubes 60, a small amount of the liquid refrigerant is siphoned into the interior of the tube by capillary action to wet the interior before the liquid refrigerant rises to a level above the upper end of the tube. Such a starting device assists in the initial wetting of the tube to insure equal distribution of refrigerant in the plurality of tubes. The liquid refrigerant will flow downwardly by gravity in the helical grooves 64 from the top to the bottom of the tubes 60 and due to the shape and size of the grooves the liquid refrigerant will creep between adjacent grooves to wet the interior surface of the tubes throughout their length. In other words, the helical serrations 64 on the interior of the evaporator tubes 60 will cause a thin film of the liquid refrigerant to be formed thereon. The liquid refrigerant in excess of that evaporated during a single pass through the evaporator tubes 60 will flow through the tubes to the lower header 53.

The pump 65 continuously recirculates the refrigerant from the lower header 53 to the upper header 52 and delivers the refrigerant through the nozzles 69 in the form of a spray to promote evaporation of the refrigerant. Due to the relatively thin film of liquid refrigerant on the internal surfaces of the tubes 60 the evaporation of the refrigerant occurs at the surface of the liquid so that liquid refrigerant will not be blown from the tubes. Furthermore the recirculation of the refrigerant insures complete and equal evaporation throughout all parts of the evaporator.

The evaporation of the refrigerant in the evaporator 10 will reduce the temperature of the refrigerant to a value corresponding to the pressure prevailing in the evaporator. Thus the evaporation of the refrigerant acts to cool the body of refrigerant supplied to the header 52 from the condenser 11 and recirculated by the pump 65. The air to be conditioned flows through the opening 51 and around the tubes 59 in the evaporator 10 and is chilled by its contact with the tubes; the air transferring its heat through the tubes to evaporate more of the refrigerant to maintain a temperature corresponding to the pressure in the evaporator.

The refrigerant vapor flows upwardly through the tubes 60 to the upper header 52 and from the lower header 53 through the relatively large passage 54 to the upper header 52 and thence flows through the pipe 15 to the absorber 14 where it is absorbed in the absorption solution. The absorption solution in the upper part of the generator 16 flows through the conduit 33, liquid heat exchanger 21 and conduit 34 to the liquid distributing pipe 35 where it is delivered into the absorber. The absorption solution in the absorber 14 is continuously recirculated through the conduit 17, pump 18 and conduit 19 to the liquid distributing pipe 42 in the absorber which delivers the absorption solution in a fine spray to promote absorption. A portion of the recirculated absorption solution is continuously diverted through the conduit 20, liquid heat exchanger 21 and conduit 22 back to the base of the generator.

If for any reason the liquid refrigerant tends to accumulate in the evaporator 10, the overflow

conduit 75 will drain the refrigerant to the conduit 22 adjacent the base of the generator to maintain the concentration of the absorption solution within permissible limits.

It will now be observed from the foregoing specification that the present invention provides an evaporator of novel construction including a plurality of vertical tubes extending between upper and lower headers. It will further be observed that the evaporator of the present invention is so constructed and arranged as to maintain a film of liquid refrigerant in all parts of the evaporator and is adapted to accommodate the large volumes of refrigerant vapor which are formed in a vacuum system. It will still further be observed that the present invention provides for continuously circulating refrigerant from the lower header to the upper header to provide an ample supply of liquid refrigerant to insure the wetting of the internal surfaces of all of the evaporator tubes.

While a preferred refrigeration system and evaporator construction are herein illustrated and described it is to be understood that other refrigeration systems may be used and that modifications may be made in the construction and arrangement of the elements in the evaporator without departing from the spirit or scope of the invention. Therefore without limiting myself in this respect reference is to be had to the appended claims for a definition of the limits of the invention.

What is claimed is:

1. An evaporator for use in a refrigeration system having an upper header provided with a horizontal tube sheet, a lower header, a plurality of vertical tubes extending between the upper and lower headers and projecting above the horizontal tube sheet of the upper header, means for supplying liquid refrigerant to the upper header which overflows into the end portions of the tubes projecting above the tube sheet, said tubes having internal serrations to retard the flow of refrigerant through the tubes to maintain a film of liquid refrigerant on the interior surfaces thereof, and means for recirculating liquid refrigerant from the lower to the upper header.

2. In an absorption refrigeration system, a generator, a condenser, an evaporator, an absorber, conduit means interconnecting the elements to provide circuits for a refrigerant and absorbent, said system operating in a partial vacuum and utilizing water as a refrigerant and a salt solution as an absorbent, said evaporator comprising a casing forming a central opening with a header above the opening, a header below the opening and a relatively large passageway between the upper and lower headers at one side of the opening, a plurality of vertical tubes extending between the upper and lower headers, means for supplying liquid refrigerant to the upper header to cause it to flow by gravity through the plurality of tubes, said interconnecting means including a conduit connecting the upper header to the absorber, and a conduit having one end extending a predetermined height above the bottom of the lower header and connected to another

part of the system to control the amount of refrigerant in the evaporator by draining excess refrigerant to the other part of the system.

3. An evaporator for use in a refrigeration system comprising a casing forming a central opening with a header above the opening, a header below the opening and a relatively large passageway between the upper and lower headers at one side of the opening, said upper header having an inlet for liquid refrigerant and an outlet for refrigerant vapor, the bottom wall of the upper header forming a horizontal tube sheet, a plurality of vertical tubes extending between the upper and lower headers with the ends of the tubes projecting above the tube sheet in the upper header, structure in the upper header for retaining a pool of liquid refrigerant which overflows into the upwardly projecting ends of the tubes, a pump in the lower header, and a conduit connecting the pump and the upper header to recirculate refrigerant from the lower header to the upper header.

4. An evaporator for use in a refrigeration system comprising a casing forming a central opening with a header above the opening, a header below the opening and a relatively large passageway between the upper and lower headers at one side of the opening, said upper header having an inlet for liquid refrigerant and an outlet for refrigerant vapor, the bottom wall of the upper header forming a horizontal tube sheet, a plurality of vertical tubes extending between the upper and lower headers with the ends of the tubes projecting above the tube sheet in the upper header, a dam in the upper header for retaining a pool of liquid refrigerant which overflows into the upwardly projecting ends of the tubes, said tubes having internal serrations to impede the flow of refrigerant therethrough and cause a wetting of the internal surface of the tubes, a pump in the lower header, and a conduit connecting the outlet from the pump to the upper header for recirculating refrigerant from the lower header to the upper header.

5. A unitary evaporator comprising a casing forming a central opening with a header above the opening, a header below the opening and a relatively large passageway between the upper and lower headers at one side of the opening, said upper header having an inlet for liquid refrigerant and an outlet for refrigerant vapor, the bottom wall of the upper header forming a horizontal tube sheet, a plurality of vertical tubes extending between the upper and lower headers, a dam in the upper header for retaining a pool of liquid refrigerant which overflows into the ends of the tubes, the end of the lower header opposite the passageway being extended horizontally and vertically at the side of the opening to provide a pump chamber, a pump in the pump chamber, an hermetically sealed motor mounted on the casing and connected to drive the pump, and a conduit connected to the outlet from the pump and extended into the upper header, said pump and conduit recirculating refrigerant from the lower to the upper header.
